UNITED STATES PATENT OFFICE.

JOHN M. CONROY, OF ALLEGHENY, PENNSYLVANIA.

FRAME FOR MIRRORS, &c.

No. 861,709.

Specification of Letters Patent.

Patented July 30, 1907.

Application filed April 30, 1907. Serial No. 371,168.

To all whom it may concern:

Be it known that I, JOHN M. CONROY, residing at Allegheny, in the county of Allegheny and State of Pennsylvania, a citizen of the United States, have invented or discovered certain new and useful Improvements in Frames for Mirrors, &c., of which improvement the following is a specification.

The invention described herein relates to certain improvements in securing mirrors, etc., in frames, and has for its object a construction whereby the glass may be rigidly fastened in the frame, the fastening means being constructed in such manner that, while firmly clamping the glass, there is no liability of injury to the same.

15 The invention is hereinafter more fully described and claimed.

In the accompanying drawings, forming a part of this specification, Figure 1 is a back elevation of a frame having the glass secured therein in accordance with my invention; Fig. 2 is an enlarged detail view showing the fastening devices; Fig. 3 is a sectional view on a plane indicated by the line III—III Fig. 2; Figs. 4 and 5 are respective detailed views of parts of the fastener.

In the practice of my invention the side bars 1 of the frame are secured together by a cross bar 2, which in the construction shown has its outer ends bent up and riveted to the side bars in such manner as to permit of the rotation of the cross-bar. Slides 3 provided on one side with grooves for the reception of the cross bar, are mounted on the latter in such manner, that when moved towards each other along the cross bar, lugs 4 will grip the edges of the glass 5. At their inner ends these slides are provided with upwardly projecting loops 6 for the reception of the ends of braces or struts 7.

35 The outer ends of these struts are provided with suitable means for interlocking with the cross bar or other stationary part of the frame. In the construction shown the ends of the struts are notched to receive the lugs on the ends of the cross bar. These struts are made of such a length relative to the position of the slots of the slides, when the latter are shifted to grip the glass, as to require an upward bowing or bending of the struts as indicated in Figs. 3 and 4 to permit of the insertion of one end of the struts into the loops 8, when the opposite

45 ends are in engagement with the cross-bar. After the slides have been moved along so that the lugs or ears thereon will engage the edges of the glass, the struts are placed in position, one end passing in the slots of the

slides and the other engaging a stationary part of the frame, the central portion of the struts are thrust down forming a reverse curve or bend, as shown in Fig. 3, in the strut and locking the same in position. The downward forcing or bending of the struts will force the slides inwardly and firmly clamp the glass in position.

The strut is made of flexible material so that it will take a set when bent to lock the slides, but the two bends or arches *a* formed by bending the strut will afford some slight resilience which will prevent the lugs of the slides from being pressed with sufficient force against the edge of the glass to injure the latter.

The slides are made of sheet metal, the groove for the reception of the cross bar being stamped therein. The loops 8 are formed by slitting the grooved portion of the slides adjacent to their inner ends and slightly stretching the portions outside of the slits.

The sides hold the glass against the cross-bar and the struts or locking pieces and slides hold the glass from movement along the cross-bar, and central between the sides of the frame.

I claim herein as my invention:

1. As a means for securing glass in frames the combination of a cross-bar secured to the sides of the frame, slides provided with lugs adapted to engage the edges of the glass and serving to hold the glass on the cross-bar and locking pieces interposed between stationary portions of the frame and shoulders on the slides whereby the lugs on the slides are held in engagement with the glass.

2. As a means for securing glass in frames, the combination of slides bearing on one side of the glass and provided with lugs adapted to engage the edges of the glass, a cross-bar secured to the sides of the frame and adapted to pass between the glass and the slides, locking pieces interposed between portions of the cross bar and shoulders on the slides.

3. As a means for securing glass in frames, the combination of slides bearing on one side of the glass, and provided with lugs adapted to engage the edges of the glass and having shoulders thereon, a cross-bar secured to the sides of the frame and adapted to pass between the glass and the slides and flexible locking pieces of lengths greater than the distances between shoulders on the slides and portions of the cross-bar, when the lugs of the slides are in engagement with the glass, said locking pieces being bent between their ends to lock the slides and locking pieces in position.

In testimony whereof, I have hereunto set my hand.

JOHN M. CONROY.
